UNITED STATES PATENT OFFICE.

SAMUEL G. STAHLHUTH, OF ST. LOUIS, MISSOURI.

HOOP-SPLITTING MACHINE.

1,244,655.

Specification of Letters Patent.

Patented Oct. 30, 1917.

Application filed August 25, 1916. Serial No. 116,803.

To all whom it may concern:

Be it known that I, SAMUEL G. STAHLHUTH, a citizen of the United States, and resident of St. Louis, Mo., have invented 5 certain new and useful Improvements in Hoop-Splitting Machines, of which the following is a specification.

This invention relates to improvements in a hoop splitting machine, especially adaptable for making head-liners out of broken hoops which head liners are used in supporting the barrel heads in proper position when once inserted.

A further object of this invention is to 15 construct a machine which can be either operated by hand or power and such hoops which are broken or otherwise too short to be used to properly encircle a barrel may be passed through said machine and split 20 in sections which sections as before stated are used for head liners in such lengths as found desirable.

Figure 1, is a side elevation of my improved invention.

Fig. 2, is a top plan view of the same.

Fig. 3, is a vertical sectional view of the same.

Fig. 4, is a central cross-sectional view taken on the line 4—4 of Fig. 1, and viewing the same in the direction as indicated by the arrow.

Fig. 5, is a detail perspective view of one of the pins made use of for feeding the hoop through the machine.

In carrying out my invention I provide a suitable frame consisting of two side members 6, and 7, each provided with a suitable journal bearing 8 in which is supported a shaft or spindle 9, on this shaft or spindle 40 is located a large gear wheel 10 which is designed to mesh with a gear pinion 11, mounted on the shaft 12, which is also supported in bearings 13, formed in each member constituting the frame. On the projecting end 14 of the shaft 12 may be applied a crank-handle by which the device may be placed in operation by hand or on said shaft 45 may be located a pulley by which the machine may be driven by power.

On the shaft 9 and located centrally between the members 6 and 7 constituting the frame is located a cutting member composed of two cutting disks 15 and 16, the outer periphery being formed to a knife edge, the 55 same if desirable spaced apart by means of

a center core 17, which is constructed preferably in the manner as that shown in sectional view of Fig. 4, the core radiating from the hub 18 by which the core is supported on the shaft 9. 60

In the core and at suitable intervals apart I provide bores or openings 19 in which are adapted to be inserted feeder pins 20, the horizontal portions 21 of the pins passing into the bores while the right angular or vertical portion 22 is directed toward the periphery of the core and permitted to be seated in grooves 23 formed in the sides of the core, the ends of said pins being wedge-shape as that indicated by the numeral 24 70 shown in Fig. 5.

These pins as shown in the illustration are arranged preferably 12 in number, 6 projecting on one side and 6 on the opposite side of the center core in a position as that 75 shown in the illustration of Fig. 2. The projecting flange ends of these pins are arranged to fit snugly against the inner face of the cutting disk and arranged to contact with the center strip of the hoop as the same 80 is being cut or split by the disks. And by these pins the hoop is fed through the machine.

In the frame and directly beneath the cutting disk is located a grooved roller 25, 85 this is also mounted on a short shaft or a pair of projecting lugs which have bearing in the journals 26 formed in the frame. The surface of the roller is provided with a pair of grooves 27 as that shown in Fig. 4 90 and in which the cutting edge of both disks project. This roller revolves by means of the frictional contact of the hoop during the rotation of the machine.

In order to permit the hoop to freely move 95 through the machine and to avoid friction I provide in the frame a pair of said frictional rollers 28, one supported on each member of the frame and supported between projecting integral lugs 29 formed on each 100 frame, the rollers passing through slots formed in such members and of such depth as to permit the periphery of each frictional roller to be shortly beyond the alignment of the inner surface of each frame. The position being clearly illustrated in Fig. 2.

On the frame and in advance of the cutting disks I place a cross bar 30 which bar is firmly fastened on each side member and straddling the same and to this bar is a 110

depending curved guide member 31 the free end of the edge to almost contact with the periphery of the core yet out of contact with the feeder pins. The purpose of this 5 guide is to direct the center portion of the hoop after the same has been cut from following the core after having been connected with by the feeder pins which in the operation are partly sunk into the hoop in order 10 to feed the same forward. The frame is also provided with a table 32 on which the hoop is placed for feeding the same against the cutting disks.

The hoops to be cut by this machine are 15 generally of such character as are not fit for use on the outside of barrels and such culls as they would be termed are placed on the table 32 and fed to the machine in the direction as indicated by the arrow A.

20 Having fully described my invention what I claim is:

1. In a hoop splitting machine the combination of a suitable frame of a pair of 25 rotating splitting disks mounted therein, and means operating in conjunction with the rotating cutting disks for feeding hoops through the machine to be split in three sections, substantially as specified.

2. A hoop splitting machine comprising 30 a frame, a rotating core, a pair of circular splitting disks connected to said core and suitably spaced apart, a plurality of feeder pins carried by the core and between the cutting disks, and means for rotating the 35 core and splitting disks for splitting a bar-

rel hoop into three sections, substantially as specified.

3. A machine of the class described comprising a suitable frame, a rotating core mounted therein, a pair of circular splitting disks carried by the rotating core, a grooved roller supported in the frame below the rotating core and in proper relation with the splitting disks, means carried by the core for feeding the hoop between the splitting disks and the grooved roller and a guide in connection with the core for directing the split sections of the hoop away from the core when the same has been cut, substantially as specified.

4. A machine of the class described comprising a suitable frame, a pair of splitting disks rotatably mounted therein, feeder pins located between said splitting disks which pins contact with the material to be 55 split for feeding the same, a grooved roller carried in the frame below the splitting disks and having its grooves located in proper relation with the splitting disks over which the material to be cut is placed 60 and a guide mechanism for directing the split section of the hoop away from the splitting disks.

In testimony whereof, I have signed my name to this specification, in presence of two 65 subscribing witnesses.

SAMUEL G. STAHLHUTH.
